United States Patent Office

Des. 203,313
Patented Dec. 21, 1965

203,313

ASH TRAY

John N. Bartlett, 88 Washington St., Denver, Colo., and
Elmer A. Osmon, 156 S. Grand Oaks, Pasadena, Calif.

Filed Apr. 26, 1965, Ser. No. 84,944

Term of patent 14 years

(Cl. D85—2)

FIG. 1.

FIG. 2.

FIG. 3.

FIG. 4.

FIGURE 1 is a perspective view of an ash tray embodying our new design;

FIGURE 2 is a side elevation view of the invention design as shown in FIGURE 1;

FIGURE 3 is an end elevation view of the invention design from the right hand end of the invention design as viewed in FIGURE 1; and

FIGURE 4 is a cross-section view taken along line 4—4 on FIGURE 1.

We claim:

The ornamental design for an ash tray, as shown.
